DESIGN FOR A TABLE LAMP

Violet Faill, Childwall, Liverpool, England, assignor to Thomas Pryce Parry and Oswald Ridley Adamson, trading as The Pandora Company, Liverpool, England, a British company

Application March 11, 1949, Serial No. 1,347
In Great Britain August 16, 1946

Term of patent 14 years

(Cl. D48—20)

To all whom it may concern:

Be it known that I, Violet Faill, a British subject, citizen of the United Kingdom and Colonies, of 18 Eldred Road, Childwall, Liverpool 16, in the county of Lancaster and Kingdom of England, have invented a new, original, and ornamental Design for a Table Lamp, of which the following is a specification, reference being had to the accompanying drawing, forming part thereof.

Fig. 1 is a front perspective view of a table lamp showing my new design; and

Fig. 2 is a rear perspective view thereof.

This application is filed as a continuation in part of my application Serial No. D. 130,634, filed February 3, 1947, now abandoned.

I claim:

The ornamental design for a table lamp, as shown.

VIOLET FAILL.
